United States Patent Office

Des. 191,186
Patented Aug. 22, 1961

191,186

BARBECUE GRILL

Aake E. Maki, Alston, Mich. (Pelkie, Mich.)

Filed June 17, 1960, Ser. No. 61,006

Term of patent 14 years

(Cl. D81—10)

Fig. 1

Fig. 2

FIG.3

FIG.5

FIG.4

FIGURE 1 is a perspective view of a barbecue grill, according to the present invention, showing my new design,

FIGURE 2 is a view of the grill, as viewed from above,

FIGURE 3 is a side elevational view, and

FIGURE 4 is a front elevational view.

FIGURE 5 is an enlarged fragmentary view showing the outer end of the rigid supporting arm in detail.

I claim:

The ornamental design for a barbecue grill, as shown.

References Cited in the file of this patent

UNITED STATES PATENTS

D. 159,180	Wehner	Jan. 22, 1949
2,768,042	Persinger et al.	Oct. 23, 1956
2,914,283	Jorgensen	Nov. 24, 1959

OTHER REFERENCES

Central Scientific Co. Catalog of Lab. Apparatus and Scientific Instruments, received November 2, 1942, page 365.

House Beautiful, November 1959, page 85, Malone's Metalcraft adv. (Copy in Div. 81 library.)